REPLACEABLE HEEL FOR SHOES

Anthony Cortina, 56 Huntington St., New London, Conn.
 Original application Aug. 21, 1963, Ser. No. 303,962.
 Divided and this application Oct. 15, 1964, Ser. No. 404,084

2 Claims. (Cl. 36—42)

This application is a division of my co-pending application, Serial No. 303,962, filed August 21, 1963, for a Replaceable Heel for Shoes.

This invention relates to readily removable shoe heel construction and particularly one which, besides being easily secured and removed, is firmly fastened both about an edge and to be resistant to rotary movement.

The several constructions, according to this invention, show alternate fastening means for quick removability while giving firm marginal securing of the heel by a flange, and further reinforcement is usually available from a core extending from an edge toward and preferably through the center. Such core braces and offsets the tendency of the heel to be dislodged in a torque or twist of the foot of the wearer.

The invention will be further described in relation to the drawings in which:

FIG. 1 illustrates a form in which the central core is laterally locked as well as reinforced by a slidable bar, the parts being positioned as they will be assembled;

FIG. 2 is a longitudinal section through the assembled heel of FIG. 1; and

FIG. 3 is an inner end view of the assembled heel of FIG. 1.

As shown in FIGS. 1 through 3 the heel 96 may be secured to the plate 93 by a latching rod 100. In this modification the plate 93 as shown in FIG. 1 has a deep groove or channel 102 pressed into it preferably from side to side, that is, athwart the heel usually at about the center portion, but it could be located somewhat forward or behind it, as desired. The same construction may be used with the latching rod slideable longitudinally, along the axes of the shoe, if desired. The heel body 96 has a corresponding slot 104 cut from side to side, or from either side at least a substantial distance inward from a side to receive a latching bar 100 mounted in the heel slot 104 extending as well into and engaging slot 102 of the plate 93. The heel is mounted on this plate 93 by sliding it inward from the rear for mounting, as in other modifications described above. The plate 93 may also have a downturned forward plate 172 for its front end which may carry a rear-turned flange 174. The flange 172 lies within and mates into the correspondingly cut away flange housing portion 180 and flange receiving slot 182 in the forward end of the heel 178. For mounting of the heel 96 of FIG. 1, it is first slid from the rear forward upon the latching plate 93 until the forward plate 172 lies and is housed flush within the cut away portion 180, and the rear-turned flange 174 lies within the groove 182.

In that assembled position the grooves 102 and 104 will be aligned for receiving the lateral sliding latching rod 100 which is slid into locking position from either side of the heel. The center part of the groove 102 may be bored and threaded at 106 to receive a threaded stud 108 which is fastened into the bore 106 after first passing through the latching bar 100. In this manner the stud 108 prevents the latching bar 100 from being displaced, and the bar 100, in turn, braces the heel against any twist or torque. The heel otherwise remains securely fastened

2

to the plate 93, as described for other modifications above, that is, by the edge of the plate 93 being retained within the groove 14 beneath the flange 12.

While, as shown, the heel of this modification is fastened by a single latching bar 100, that bar may be substituted by two bars, one inserted from each side, and each having a fastening screw 108 for securing the same; or alternatively, a single shorter section of a bar may be inserted from either side for a short distance to extend slightly beyond the heel center, to have a substantially equal latching effect to prevent rotary torque. Of course the screw fastener 108 can be substituted by other fastening means; for instance, a fastener 38 as shown in FIG. 1 may be inserted upward from the bottom of the heel 96 in the dotted line position thereof, the shank of the screw being passed through the latch 100 and being threaded into the bore 106 for screw threaded securement of the assembly. The stud 108 may be countersunk below the surface of the heel. Moreover, such screw fastener modification as described in my parent application will be equally suitable for fastening the heel to the plate 93.

Other modifications of the constructions shown will occur to those skilled in the art within the spirit of this invention and it is accordingly intended that the several descriptions be regarded as illustrative and not limiting except as defined in the claims appended hereto.

I claim:

1. A readily removable heel structure comprising a heel shaped retaining plate having plane sides rounded at the rear, spacing means for mounting said plate below the heel area of a shoe body, said retaining plate having side and rear edges extending outwardly of said spacing means for support of a heel thereon, said plate having a deep channel press formed therein, with the channel opening downward thereof, a heel having a flange disposed inward around the edge of its upper surface cooperative with the spaced edges of the retaining plate for sliding securement of said heel on said plate with the flange of said heel adapted to be retained between the plate and shoe body, said heel having a deep channel formed inwardly from a vertical side toward the center thereof with its channel opening upward and aligned with the said channel formed in said plate, a fastening plug, said channels being aligned together to house and retain the fastening plug in sliding fit therein and securing said heel in engaged position of said flange upon said retaining plate.

2. The heel as defined in claim 1 having fastening means securing said plug from disengagement in said channel.
